US0D1007330S

(12) **United States Design Patent** (10) Patent No.: **US D1,007,330 S**
 Johnson et al. (45) Date of Patent: ** Dec. 12, 2023

(54) **CONTAINER TRAY**

(71) Applicants: **DFA Dairy Brands IP, LLC**, Dallas, TX (US); **Dordan Manufacturing Co.**, Woodstock, IL (US)

(72) Inventors: **Brett A. Johnson**, Belvidere, IL (US); **John Kreider**, Woodstock, IL (US); **Daniel J. Slavin**, Village of Lakewood, IL (US)

(73) Assignees: **DFA Dairy Brands IP, LLC**, Dallas, TX (US); **Dordan Manufacturing Co.**, Woodstock, IL (US)

(**) Term: **15 Years**

(21) Appl. No.: **29/695,984**

(22) Filed: **Jun. 24, 2019**

Related U.S. Application Data

(62) Division of application No. 29/579,237, filed on Sep. 28, 2016, now Pat. No. Des. 854,423.

(51) **LOC (14) Cl.** **09-03**

(52) **U.S. Cl.**

USPC **D9/737; D9/434**

(57) CLAIM

The ornamental design for the container tray, as shown and described.

DESCRIPTION

FIG. 1 is a top perspective view of a first embodiment of container tray illustrating our new design;
 FIG. 2 is a bottom perspective view of the first embodiment of container tray;
 FIG. 3 is a back cross-sectional view of the first embodiment of container tray taken along line 3 of FIG. 2;
 FIG. 4 is a front cross-sectional view of the first embodiment of container tray taken along line 4 of FIG. 2;
 FIG. 5 is a right side cross-sectional side view of the first embodiment of container tray taken along line 5 of FIG. 2;
 FIG. 6 is a left side cross-sectional view of the first embodiment of container tray taken along line 6 of FIG. 2;
 FIG. 7 is a top view of the first embodiment of container tray;
 FIG. 8 is a bottom view of the first embodiment of container tray;
 FIG. 9 is a detailed view of the area that is within the dashed dotted circle of FIG. 1;
 FIG. 10 is a detailed view of the area that is within the dashed dotted circle of FIG. 2;
 FIG. 11 is a detailed view of the area that is within the dashed dotted circle of FIG. 3;
 FIG. 12 is a detailed view of the area that is within the dashed dotted circle of FIG. 5;
 FIG. 13 is a detailed view of the area that is within the dashed dotted circle of FIG. 7;

FIG. 14 is a detailed view of the area that is within the dashed dotted circle of FIG. 8;
FIG. 15 is a top perspective view of a second embodiment of container tray illustrating our new design;
FIG. 16 is a bottom perspective view of the second embodiment of container tray;
FIG. 17 is a back cross-sectional view of the second embodiment of container tray taken along line 17 of FIG. 16;
FIG. 18 is a front cross-sectional view of the second embodiment of container tray taken along line 18 of FIG. 16;
FIG. 19 is a right side cross-sectional view of the second embodiment of container tray taken along line 19 of FIG. 16;
FIG. 20 is a left side cross-sectional view of the second embodiment of container tray taken along line 20 of FIG. 16;
FIG. 21 is a top view of the second embodiment of container tray;
FIG. 22 is a bottom view of the second embodiment of container tray;

FIG. 23 is a detailed view of the area that is within the dashed dotted circle of FIG. 15;
FIG. 24 is a detailed view of the area that is within the dashed dotted circle of FIG. 16;
FIG. 25 is a detailed view of the area that is within the dashed dotted circle of FIG. 17;
FIG. 26 is a detailed view of the area that is within the dashed dotted circle of FIG. 19;
FIG. 27 is a detailed view of the area that is within the dashed dotted circle of FIG. 21; and,
FIG. 28 is a detailed view of the area that is within the dashed dotted circle of FIG. 22.
The dash-dot broken lines represent the bounds of enlarged views. The dash-dash broken lines illustrate portions of the container tray. The broken lines form no part of the claimed design.
